UNITED STATES PATENT OFFICE

ROSS MOORE, OF COLUMBUS, OHIO

DESIGN FOR A LAMP

Application filed September 10, 1931. Serial No. 41,053. Term of patent 3½ years.

To all whom it may concern:

Be it known that I, Ross MOORE, a citizen of the United States, residing at Columbus, in the county of Franklin and State of Ohio, have invented a new, original, and ornamental Design for a Lamp, of which the following is a specification, reference being had to the accompanying drawings, forming part thereof.

I claim:

The ornamental design for a lamp, as shown.

ROSS MOORE.
